UNITED STATES PATENT OFFICE.

EDNA ECKERT, OF NEWARK, NEW JERSEY.

DESIGN FOR A SHRINE.

Application filed November 19, 1928. Serial No. 28,934. Term of patent 3½ years.

To all whom it may concern:

Be it known that I, EDNA ECKERT, a citizen of the United States, residing at 300 Verona Avenue, Newark, in the county of Essex and State of New Jersey, have invented a new, original, and ornamental Design for a Shrine, of which the following is a specification, reference being had to the accompanying drawing forming part thereof.

In the accompanying drawing:

Fig. 1 is a front elevation of the shrine, showing my new design; and

Fig. 2 is a side elevation thereof.

I claim:

The ornamental design for a shrine, substantially as shown.

EDNA ECKERT.
